UNITED STATES PATENT OFFICE.

JAMES P. WOOD, OF BASTROP, TEXAS.

ATTACHMENT FOR PIVOT POLISHERS.

Application filed September 12, 1925. Serial No. 55,983.

This invention relates to new and useful improvements in attachments for pivot polishers.

The object of the invention is to provide an attachment for lapping or polishing which may be minutely adjusted, laterally as well as vertically.

Another object of the invention is to provide means for rocking the tool spindle for burnishing or grinding the pivot.

A still further object is to provide a longitudinally movable tool spindle in combination with a belt hanger adjustable to position the spindle.

15 An important object of the invention is to provide a supporting bracket and shank arranged for giving the proper vertical and horizontal adjustment on the slide rest.

20 A construction designed to carry out the invention will be hereinafter described together with other features of the invention.

The invention will be more readily understood from a reading of the following specification and by reference to the accompanying drawings, in which an example of the invention is shown, and wherein:

25 Fig. 1 is a partial side elevation of a jeweler's lathe and slide rest equipped with an attachment constructed in accordance with 30 my invention,

Fig. 2 is a plan view of the same,

Fig. 3 is a side view of the belt hanger or tightener,

Fig. 4 is a sectional view of the pulley 35 mounting,

Fig. 5 is a perspective view of one of the pulley retainers,

Fig. 6 is an enlarged sectional view taken on the line 6—6 of Fig. 2,

40 Fig. 7 is an enlarged sectional view on the line 7—7 of Fig. 2,

Fig. 8 is an enlarged sectional view on the line 8—8 of Fig. 2,

45 Fig. 9 is an enlarged sectional view on the line 9—9 of Fig. 2,

Fig. 10 is a plan view of the lock washer for the post adjusting screw,

Fig. 11 is a detail of the lower end of the said screw, and

50 Fig. 12 is a sectional view of the rocker spring and parts.

In the drawings the numeral 10 designates a suitable slide rest which may be of any suitable design, either as shown in the said 55 drawings or as is shown in my co-pending

application filed of even date herewith. The slide rest includes a stud 11 in which a slide bar 12 is confined by a set screw 13. The stud is rotatably adjustable and its supports are horizontally adjustable. The bar 12 is 60 horizontally adjustable.

A right angular hanger 14 depends from the end of the bar. The enlarged circular base 15 of an upright tubular post 16 is fastened on the horizontal member of the hanger, by means of screws 17 (Fig. 6). Concentrically within the bore of the post and its base is mounted a vertical adjusting screw 18 which is threaded and has a groove 19 (Fig. 11) around its lower end for receiving a lock washer 20 (Fig. 10). The screw is centered in the bore of the post by engaging in an opening 21 (Figs. 6 and 7) in the hanger 14, while the washer 20 rests upon the hanger and is confined by the base 75 15. The bore of the post receives the tubular shank 22 of the lapping attachment which is threaded to receive the screw 18.

The lapping attachment is an important part of the device. The tubular shank 22 80 has fixed to its upper end a right angular brackets 23 from which a pair of pilot pins 24 depend. These pins engage in wells 25 in the post and prevent the shank and bracket from rotating, but permit a free vertical movement. The screw 18 has a turning button 26 on its upper end. For fastening the shank in adjusted positions I provide a set screw 27 threaded through the post 16 to engage the shank and having a jamb nut 28 85 90 for locking the screw.

A horizontal arm 29 extends from the bracket 23 at right angles thereto, and its outer portion forms one side of a rectangular frame 30. Between the frame members 95 and parallel to the arm a rocker 31 is pivoted. The rocker has a yoke handle 32 overhanging said arm. The rocker (Fig. 9) is U-shaped and has a sleeve bearing 33 at its rear end and a sleeve bearing 34 at its front 100 end. A spindle 35 rotatable in the sleeve is free to slide longitudinally. A handle 36 (Fig. 2) is confined on the rear end of the spindle. The forward end of the spindle is reduced so that a lapping tool 37 may be 105 frictionally engaged thereon.

The front sleeve 34 is disposed between standards 38 fixed on the frame 30 and rocks between stop screws 39 (Fig. 8) threaded through said standards. Jamb nuts 40 are 110

2
mounted on the screws for holding them in adjusted positions. A curved tension spring 41 (Figs. 9 and 12) is fastened on the frame and engages the rear sleeve 33. This spring 5 will act to swing the rocker and hold the sleeve 33 in contact with one of the screws 39. The swing of the rocker is limited by the spacing of the screws and when the handle 32 is depressed and released the 10 spring will swing the rocker to its normal position.

On the shaft 35 a small pulley 42 is fastened and is driven by an endless belt 43 one end of which passes around said pulley. 15 This belt passes over a pair of idler pulleys 44 and is driven from the usual counter shaft (not shown). The pulleys 44 are mounted on trunnions 45 (Fig. 4) projecting from each side of a hub 46 carried by a 20 hanger 47 which is centrally pivoted on a bracket 48. The bracket is slidably mounted on a square vertical staff 49. The bracket has a horizontal set screw 50 threaded therein and engaging the staff and carrying a 25 jamb nut 51. The staff is graduated and the bracket is fastened at different elevations by the parts 50 and 51. The hanger has a longitudinal set screw 52 and a jamb locking nut 53, whereby the hanger and 30 pulleys 44 may be adjusted in a vertical plane and fastened. In order to confine the pulleys 44 on the trunnions 45 I employ flanged collars 54 (Fig. 5) slotted at 55 to receive a pin 56 passing through (Fig. 4) 35 the trunnion.

As is shown in Fig. 2 the lapping attachment is mounted so that the tool 37 is in 40 position to act on the pivot which latter is set up in the lathe parallel to the face of the said tool. To adjust the lapping tool to the proper angle the slide rest 10 and the stud 11 are adjusted in the usual manner. To 45 vertically adjust the attachment so that the transverse center of the face of the lapping tool will be either parallel with, below or above the longitudinal axis of the pivot, the screw 27 is loosened and the screw 18 is turned by the button 26. If it is desired to hold the lapping tool against the work or 50 spaced therefrom the hanger 47 is swung, whereby the pulley 42 and spindle 35 will

be shifted. The bracket 48 permits various adjustments of the belt.

The staff 49 is swiveled in the frame 30 and fastened by a screw 57. When the tool 55 37 and its spindle 35 are swung on an angle so that the belt 43 might be thrown off the pulleys 44, said screw 57 is loosened and the staff turned so that the pulleys 44 are alined with the counter shaft. 60

What I claim, is:

1. In a pivot polisher attachment, a post supporting bar, a tubular post fixed thereon, a spindle support having an interiorly threaded shank disposed within the bore of 65 said post, a screw threaded through said shank to vertically adjust the same and retained in said bar against axial movement, a spindle carrying a polishing tool mounted upon the spindle support, and driving 70 means for the spindle carried by said support.

2. In a pivot polisher attachment, a post supporting bar, a tubular post fixed thereon, 75 a spindle support at one side of said post having an extended arm carrying an interiorly threaded shank disposed within the bore of said post, a screw threaded through said shank to vertically adjust the same and seated within the bar against axial movement, a spindle carrying a polishing tool mounted upon the spindle support, and a staff upon said support carrying driving members for the spindle. 80

3. In a pivot polisher attachment, an angular hanger, means for horizontally adjusting the same, a vertical tubular post fixed upon the horizontal bar of the hanger, a spindle frame carrying an interiorly threaded shank disposed in said tubular post, an elongated pin on said frame seated in a well in the post to prevent rotative movement of the shank with respect to the tubular post, a screw retained in said bar against axial movement and threaded through said shank 95 with an operating means at the upper end of the screw, and a spindle carrying a polishing tool adjustably mounted upon said frame. 90

In testimony whereof I affix my signature.

JAMES P. WOOD.
